(57) **CLAIM**

The ornamental design for a tapered cup, as shown and described.

DESCRIPTION

FIG. 1 is a front perspective view of a first embodiment of our new design for a tapered cup;

FIG. 2 is a front elevation view thereof, the right, left and rear elevation views being substantially the same as the front elevation view;

FIG. 3 is a top plan view thereof;

FIG. 4 is a bottom plan view thereof;

FIG. 5 is a cross-sectional elevation view of the cup of FIG. 1 taken at line 5-5 of FIG. 3;

FIG. 6 is a front perspective view of a second embodiment of our new design for a tapered cup;

FIG. 7 is a front elevation view of the tapered cup of FIG. 6, the right, left and rear elevation views being substantially the same as the front elevation view;

FIG. 8 is a top plan view of the tapered cup of FIG. 6;

FIG. 9 is a bottom plan view of the tapered cup of FIG. 6; FIG. 10 is a cross-sectional elevation view of the cup of FIG. 6 taken at line 10-10 of FIG. 8;

FIG. 11 is a front perspective view of a third embodiment of our new design for a tapered cup;

FIG. 12 is a front elevation view of the tapered cup of FIG. 11, the right, left and rear elevation views being substantially the same as the front elevation view;

FIG. 13 is a top plan view of the tapered cup of FIG. 11;

FIG. 14 is a bottom plan view of the tapered cup of FIG. 11; and,

FIG. 15 is a cross-sectional elevation view of the cup of FIG. 11 taken at line 15-15 of FIG. 13.

The portions of the tapered cup shown in broken line form no part of the claimed design. The broken line arrows in FIGS. 3, 10, and 15 depict cross sectional view indicia and form no part of the claimed design.
